N. S. Wedder, of Troy, N.Y.
Assignor to Potter & Co. of same place.
Letters Patent No. 1186. Dated Jan'y 3, 1860.

The schedule referred to in these ^{drawings} Letters Patent and making part of the same.

To all whom it may concern,

Be it known that I, N. S. Wedder, of the City of Troy,
in the County of Rensselaer, and State of New York, have invented or produced
a new and original design for Stove Plates, and I do hereby declare that the
following is a full and exact description of the same, reference being had to the
annexed photographic drawing making a part of this specification.

My said design consists of the ornament k, arranged upon
the central part, and the ornament l, in each corner, of an oblong, rectangular
panel, upon the middle of the plate; and a sunk panel, m, upon each curved end of
the plate, as shown in the annexed drawing.

What I claim as my invention or production and desire to
secure by Letters Patent, is the ornamental design herein described and represented
in the annexed photographic drawing, for Stove plates.
